UNITED STATES PATENT OFFICE.

LOUIS GICLAS, OF WASHINGTON, DISTRICT OF COLUMBIA.

RECEIVER FOR MILK-BOTTLES AND THE LIKE.

1,276,750.

Specification of Letters Patent. Patented Aug. 27, 1918.

Application filed June 13, 1916, Serial No. 103,565. Renewed March 7, 1918. Serial No. 221,095.

To all whom it may concern:

Be it known that I, LOUIS GICLAS, citizen of the United States, residing at Washington, D. C., has invented certain new and useful Improvements in Receivers for Milk-Bottles and the like, of which the following is a specification, reference being had therein to the accompanying drawing.

This invention relates to receivers for milk bottles and the like, the same being in the nature of an attachment for door frames or equivalent structures, capable of being removably secured in place without unduly marring the construction or parts of the frame.

The invention contemplates the provision of a device into which a milk bottle may be readily introduced but from which the bottle cannot be withdrawn save upon opening the door adjacent to which the receiver is mounted.

The invention further embraces a device of the character stated provided with a securing means adapted to occupy a relatively permanent relation to the door frame, and complemental securing means carried by the receiver proper, enabling the receiver to be mounted in position, for example at night, and removed therefrom, as in the day time, so that when not in service the receiver may be put away to constitute no serious or unsightly projection or obstruction on the door frame.

A still further characteristic of the invention resides in the provision of means related to the bottom of the receiver for automatically interlocking with the top of the inserted bottle to prevent opening of the closure through which the bottle is inserted, and abstraction of the bottle through the inlet opening, the interlocking means preferably comprising elements respectively to contact with bottles of varying sizes, as for instance, quart and pint bottles.

The invention still further embraces a receiver provided with bottle interlocking means at one side of the receiver, and detachable fastening means enabling the interlocking part to be removed so that various receivers may be nested for the purpose of shipping, storage and the like.

In the accompanying drawings forming part thereof I have illustrated the preferred embodiment of the invention presenting the advantageous features of construction here-

in above noted, and the improved details in the construction and arrangement of parts will be apparent upon an inspection of such drawings in connection with the detailed description hereinafter contained.

60

In the drawings:

Figure 1 is a perspective view of a portion of a door way and frame in connection with which my bottle receiver is employed, the latter being shown in operative position;

65

Fig. 2 is a vertical sectional view through the receiver;

Fig. 3 is a horizontal sectional view looking downwardly, the receiver being shown in operative position in full lines and the inoperative position being indicated in dotted lines;

70

Fig. 4 is a rear elevation, certain parts being shown in section;

Figs. 5, 6, 7 and 8 are detail views.

75

Referring more specifically to the drawings wherein like reference characters designate corresponding parts in several views, A represents the body of the receiver having an open rear side B adapted when in position to be closed by the usual door C, the inner side wall of the container being offset slightly as at D and carried rearwardly as at E to fit behind the customary parting bead of the door frame and between the inner surface of the frame and the edge of the door, as shown. G is a supporting strip preferably secured to the face of the frame on the interior of the room or building to which the device is to be applied, said strip carrying sleeves g within which complemental hinge pintles g' engage to permit the receiver to be swung to the outside of the door or to the inside of the hall as the case may be.

80

The securing flange E is wider at its lower than at its upper end to afford an inclined edge causing the line of hinge to be correspondingly inclined, (see Fig. 1) which will enable the force of gravity to exert a tendency to swing the device into close relation to the door frame to which it is attached, when in operative position.

90

The front and opposite sides of the receiver are closed and the top is also closed save for a slot I which will permit the introduction of mail matter, it being obvious that the receiver may be utilized for that additional purpose, pivoted spring clips J being also secured to one side of the container.

95

100

110

to accommodate and retain newspapers and the like.

- K, K' represent the two members or flaps of an inwardly opening bottom, the flaps being hinged to the lower ends of the side walls of the receiver as indicated at k, and being supported when in a horizontal plane,—the closed position of the bottom,—by inwardly turned flanges L on the front and sides of 10 the receiver and by a transverse connecting and supporting wire M bridging the inner open side of the receiver and extending around the free marginal side edge and top of the latter.
- 15 The lower edge of the receiver and supporting flanges to which I have just alluded are in a plane inclined upwardly and outwardly from the inner open back of the receiver to the front wall thereof to present 20 a correspondingly inclined bottom acting when a bottle has been inserted through the bottom to tilt the bottle inwardly from a true vertical plane to an inclined position with the mouth of the bottle directed toward 25 the inner open side of the receiver, the upper portion of said open side being provided with a number of overhanging ledges or stops N (three being illustrated) adapted to engage the mouth of the bottle, one ledge or 30 stop being designed for a quart bottle another for a pint bottle, and the third for a half-pint bottle. The locking of the bottle is effected between the appropriate stop or ledge and bottom to effectually prevent 35 opening of the bottom and the withdrawal of the bottle through said bottom. The normal manner of removing the bottle by authorized persons, is to open the door to expose the inner open back of the receiver, 40 when the lower portion of the bottle may be grasped by the hand to tilt the bottle forwardly out of engagement with the ledge or stop N when the bottle may be taken out bottom-first through the open inner side of 45 the receiver. The lower ledge or stop N is pivoted as at n so as to swing outwardly from the receiver when the door is opened to permit the larger sized bottles being more readily removed.
- 50 The forward edges of the bottom parts or flaps K K' are provided with flanges decreasing in height toward the opposite sides of the receiver to which the bottom members are hinged, the function of the same being 55 to prevent the bottom members or flaps occupying a vertical position, or a position beyond the vertical plane which will prevent automatic closing of the bottom, the arrangement being such that the members 60 when open to their full extent incline inwardly or relatively converge upwardly so as to fall by gravity immediately upon the bottle being forced into the receiver to an elevation sufficient to free the bottom members or flaps and let them fall, it being ob-

vious that the flaps when closed beneath the bottle will constitute an adequate support for the bottle.

The inner ends of the bottom members or flaps K K' overlap when closed whereas the outward adjacent edges thereof are spaced to afford a forwardly flaring opening O, affording access for the finger in holding the bottle above the bottom while the latter is closing and permitting withdrawal of the finger and seating of the bottle on the bottom when closed.

The diverging relation of the edges of the flaps K K' cause them to incline toward the front wall of the receiver when 80 the flaps are raised, permitting the bottle to remain upright while settling with the flaps (Fig. 2) until the latter close and throw the bottle into the inclined stop-engaging position.

The inclined flanges at the forward ends of the bottom members or flaps K K' being bodily deflected at right angles to the plane of the bottom members assist in tilting the bottle into position to have the mouth of the 90 bottle engage the appropriate ledge or stop.

It will be apparent that in manufacturing devices of the kind under consideration, and shipping the same in quantities, when it will be found expedient to nest the receivers, it 95 is advantageous that the part constituting the stops or ledges for the upper ends or mouths of the bottles be detachable with respect to the opposite side walls of the receiver. To this end the stops or ledges are 100 formed by suitably bending a sheet of metal P as shown and providing the same along opposite edges with securing lugs or ears p adapted to be inserted through corresponding apertures p' in said opposite side walls 105 and then bent downwardly upon the outer surfaces of the side walls to secure the parts together. This arrangement will permit the devices to be shipped in a nested relation as stated, while enabling the user to expeditiously and securely assemble the same into 110 operative condition.

At times it may be desirable to use the device exclusively as a mail receiver, and on such occasions to prevent opening of the bottom, I provide a third flap member Q adapted to be thrown downwardly over the bottom flap members and be there held by a spring R engaging the squared shank q of the flap member Q, this same spring and squared shank coacting to hold the flap member Q in inoperative position parallel to the front wall of the receiver when the device is normally acting as a bottle holder.

While I have herein disclosed a preferred 125 embodiment of the invention, it will be apparent, to persons skilled in the art to which the invention appertains, that various modifications and changes may be made to constitute other embodiments of the in- 130

vention, as may be in keeping with the spirit and scope of the hereto appended claims.

Having thus described the invention, what I claim is:—

- 5 1. The combination with a frame member adjoining a way, of a movable closure for said way operatively associated with said frame member, a receiver, and means for mounting the receiver to permit the same 10 to be swung to an operative position adjacent the outer side of said closure or to a reverse inoperative position adjacent to the inner side of the closure, substantially as described.
- 15 2. The combination with a frame member adjoining a way, of a movable closure for said way operatively associated with said frame member, a receiver, and means for mounting the receiver to permit the same 20 to be swung to an operative position adjacent the outer side of said closure or to a reverse inoperative position adjacent to the inner side of the closure, said means comprising complementary separable parts 25 preventing removal of the receiver when the same occupies its position outside of the movable closure but enabling removal of the receiver when the same occupies its position inside the closure.
- 30 3. A device of the character described comprising a receiver, and means for mounting the same to permit the receiver to be swung to a position outside of a door way, or to a reverse position inside of a door way, 35 said means comprising a hinge member adapted to be secured to the frame of a door way, and a companion hinge member formed with a receiver including an inwardly extending flange and an offset part intermediate 40 of said flange and a side wall of the receiver adapted to conform to the parting bead and the adjoining inner face of the frame of a door way.
- 45 4. A device of the character described comprising a receiver having an inwardly opening bottom through which a bottle may be introduced, and means in the receiver normally permitting such introduction of the bottle through the bottom but arranged 50 to engage the bottle and coöperate therethrough with the bottom to prevent opening of the latter.
- 55 5. A device of the character described comprising a receiver having an inclined bottom portion past which a bottle may be introduced, and a stop at one side of the receiver adapted to engage the upper end of a bottle when tilted on said inclined bottom portion to lock the bottom in closed position.
- 60 6. A device of the character described comprising a receiver having a hinged bottom portion past which the article to be inserted may be introduced, said bottom portion being hinged to open inwardly and
- having a projecting part adapted to engage the side wall of the receiver to which the member is hinged to prevent the hinged bottom assuming a vertical position to maintain said member in position to fall by gravity 70 to closed position.
7. A device of the character described comprising a receiver having a hinged bottom portion past which the article to be inserted may be introduced, said bottom portion being hinged to open inwardly and having a projecting part adapted to engage the side wall of the receiver to which the member is hinged to maintain said member in position to fall by gravity to closed position, said projecting part comprising a tapering flange at the end of the bottom member. 75
8. A device of the character described comprising a receiver having a hinged bottom portion past which the article to be inserted may be introduced, said bottom portion being hinged to open inwardly and having a projecting part adapted to engage the side wall of the receiver to which the member is hinged to maintain said member in position to fall by gravity to closed position, said projecting part comprising a tapering flange at the end of the bottom member. 80
9. A device of the character described comprising a receiver having a hinged bottom portion past which the article to be inserted may be introduced, said bottom portion being hinged to open inwardly and having a projecting part adapted to engage the side wall of the receiver to which the member is hinged to maintain said member in position to fall by gravity to closed position, said projecting part comprising a tapering flange at the end of the bottom member. 85
10. A device of the character described comprising a receiver having an inclined inwardly opening bottom member past which the article to be inserted may be introduced, said bottom member at its relatively elevated end being provided with a forwardly projecting flange disposed at right angles to the plane of the bottom member, said bottom member and its flange being adapted 90 to tilt the article when the bottom is closed, and a stop member in the receiver adapted to engage the tilted article for the purpose set forth. 95
11. A device of the character described comprising a receiver having an inclined inwardly opening bottom member past which the article to be inserted may be introduced, said bottom member at its relatively elevated end being provided with a forwardly projecting flange disposed at right angles to the plane of the bottom member, said bottom member and its flange being adapted 100 to tilt the article when the bottom is closed, and a stop member in the receiver adapted to engage the tilted article for the purpose set forth. 105
12. A receiver of the character described provided with an inwardly opening bottom member past which a bottle may be introduced, and devices on the receiver normally permitting such introduction of the bottle through the bottom but arranged to engage 110 different sized bottles and respectively coöperate through the bottle with the closed bottom to prevent opening of the latter.
13. A receiver of the character described provided with an inwardly opening bottom member past which a bottle may be introduced, and devices on the receiver adapted to engage different sized bottles and respectively coöperate through the bottle with the closed bottom to prevent opening of the latter. 115
14. A receiver of the character described provided with an inwardly opening bottom member past which a bottle may be introduced, and devices on the receiver adapted to engage different sized bottles and respectively coöperate through the bottle with the closed bottom to prevent opening of the latter. 120
15. A receiver of the character described provided with an inwardly opening bottom member past which a bottle may be introduced, and devices on the receiver adapted to engage different sized bottles and respectively coöperate through the bottle with the closed bottom to prevent opening of the latter. 125
16. A receiver of the character described provided with an inwardly opening bottom member past which a bottle may be introduced, and devices on the receiver adapted to engage different sized bottles and respectively coöperate through the bottle with the closed bottom to prevent opening of the latter. 130

- 21
- latter, the bottom member occupying an inclined position and the stop members a position to engage the bottles when tilted on the bottom member.
- 5 12. A device of the character described comprising a receiver having a bottom member comprising adjacent overlapping hinged flaps adapted to open inwardly to permit introduction of the bottle, said flaps having 10 their inner edges diverging toward one end to space apart adjacent portions thereof to permit the finger to be withdrawn when lowering the bottle on the closed flaps and to permit the flaps to close while the bottle 15 is supported by said finger.
13. A device of the character described comprising a receiver having an inclined bottom portion adapted to open inwardly to permit a bottle to be introduced, and a stop 20 member at one side of the receiver, said side of the receiver being otherwise open, the stop member being arranged to engage the bottle when tilted on said bottom for the purpose set forth.
- 25 14. A device of the character described comprising a receiver having an inclined bottom portion adapted to open inwardly to permit a bottle to be introduced, and a stop member at one side of the receiver, said side 30 of the receiver being otherwise open, the stop member being arranged to engage the bottle when tilted on said bottom, said stop member comprising a part having means for removably securing the same to the body of the receiver.
- 35 15. A device of the character described comprising a receiver having a bottom portion through which the bottle may be introduced and an open rear portion through 40 which the bottle may be removed, and detachable means adjacent said open rear portion adapted to engage the bottle to prevent opening of the bottom portion, said detachable means permitting a series of the devices 45 to be nested for the purpose set forth.
16. A device of the character described comprising a receiver having front sides and top and an open rear portion through 50 which a bottle may be tilted and removed, a bottom portion comprising hinged flaps adapted to open inwardly to permit the introduction of the bottle, means bridging the open rear lower edges of the receiver formed to constitute a support for the bottom when closed, and a stop on the inside 55 of the receiver coöoperating through the bottle with the hinged flaps to prevent opening of the latter.
- 60 17. A device of the character described comprising a bottom including a pair of overlapping hinged members adapted to open inwardly to permit the introduction 65 of a bottle, and means adapted to engage the upper member to thereby hold both of the bottom members in closed position, substantially as and for the purpose described. 35
18. A device of the character described comprising a bottom including a pair of hinged members adapted to open inwardly to permit the introduction of a bottle, and means adapted to hold the bottom members in closed position, said means comprising a flap adapted to overlie the bottom members and having means acting automatically to hold the flap either in operative position or 70 in inoperative position. 75
19. A device of the character described comprising a receiver having a hinged bottom portion past which the article to be inserted may be introduced, said bottom portion being hinged to open inwardly, and a projecting part adapted to occupy a position between the side wall of the receiver and the hinged bottom portion when opened to maintain the latter in position to fall by 80 gravity to closed position. 85
20. A device of the character described comprising a receiver having a bottom member comprising adjacent hinged flaps adapted to open inwardly to permit introduction 90 of the bottle, said flaps when closed occupying an inclined plane and the edges of the flaps diverging outwardly to provide a space near the outer ends of the flaps, and a stop member to engage the upper ends of a bottle 95 when tilted by the inclined bottom, substantially as described.
21. A device of the character described, comprising a receiver having an inclined bottom portion adapted to open inwardly 100 to permit a bottle to be introduced, and a plurality of stop members at one side of the receiver, the stop members being arranged to engage bottles of different sizes when tilted on said bottom for the purpose set 105 forth.
22. A device of the character described comprising a receiver having an inclined bottom portion adapted to open inwardly 110 to permit a bottle to be introduced, and a plurality of stop members at one side of the receiver, the stop members being arranged to engage bottles of different sizes when tilted on said bottom, the lower stop member being movably mounted and located adjacent to an opening through which the bottle may be drawn for the purpose described. 115
